(57) **CLAIM**

The ornamental design for a storage bag as shown and described.

DESCRIPTION

FIG. 1 is a perspective view of a storage bag showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a reference view thereof showing the storage bag mounted on a computer and in an open status;

FIG. 10 is a reference view thereof showing the storage bag mounted on a computer as a wrist rest;

FIG. 11 is a perspective reference view thereof showing the storage bag mounted on a computer and leaned against the computer; and,

FIG. 12 is a left side reference view thereof showing the storage bag mounted on a computer and leaned against the computer.

The broken lines illustrate portions of the storage bag that form no part of the claimed design.
